US0D1088187S

(12) **United States Design Patent** (10) **Patent No.:** **US D1,088,187 S**
(45) **Date of Patent:** **** Aug. 12, 2025**

(54) **FAUCET HEAD**

(71) Applicant: **ASSA ABLOY Americas Residential Inc.**, New Haven, CT (US)

(72) Inventor: **Cameron Lee Potter**, Tustin, CA (US)

(73) Assignee: **ASSA ABLOY Americas Residential Inc.**, New Haven, CT (US)

(**) Term: **15 Years**

(21) Appl. No.: **29/977,525**

(22) Filed: **Dec. 9, 2024**

Related U.S. Application Data

(62) Division of application No. 29/881,806, filed on Jan. 6, 2023, now Pat. No. Des. 1,059,549.

(57) **CLAIM**

An ornamental design for a faucet head as shown and described.

DESCRIPTION

FIG. 1 is a top perspective view of an exemplary faucet head according to a new design;

FIG. 2 is a bottom perspective view thereof;

FIG. 3 is a right side view thereof;

FIG. 4 is a left side view thereof;

FIG. 5 is a front view thereof;

FIG. 6 is a back view thereof;

FIG. 7 is a top view thereof;

FIG. 8 is a bottom view thereof;

FIG. 9 is another left side view thereof and in a first pivot position; and,

FIG. 10 is another left side view thereof and in a second pivot position.

The portions depicted in broken lines form no part of the claimed design. The portions depicted in dash-dot lines represent boundary lines also form no part of the claimed design.

1 Claim, 10 Drawing Sheets
